ABSTRACT

A *Chrysanthemum* plant named 'Zanmukatyl' characterized by its medium sized blooms with yellow ray florets and an orange center, and prolific branching; natural season flowering date September 9-14 (week 37); blooming for a period of 5 weeks.

3 Drawing Sheets

1

Botanical designation: *Chrysanthemum×morifolium* Ramat.
Cultivar denomination: 'Zanmukatyl'.

RELATED CULTIVARS

This new plant is a mutant obtained from the *Chrysanthemum* plant 'Katelli' (U.S. Plant Pat. No. 16,674).

BACKGROUND OF THE INVENTION

The present invention relates to a new and distinct cultivar of *Chrysanthemum* plant, botanically known as *Chrysanthemum×morifolium* Ramat., commercially known as a garden mum, and hereinafter referred to by the cultivar denomination 'Zanmukatyl'. 'Zanmukatyl' is a product of a breeding and selection program for outdoor pot mums (garden mums) which had the objective of finding color mutants from existing parent plants. The new plant comprises a whole plant mutation from the *Chrysanthemum* plant named 'Katelli'. Plants of the new cultivar 'Zanmukatyl' differ from plants of the parent in the color of the inflorescences; the inflorescences are yellow with an orange center in 'Zanmukatyl' and orange with a dark red center in 'Katelli'.

The new and distinct cultivar was discovered and selected as a flowering plant by Henricus Cornelius Maria Jacobs on a cultivated field in Rijsenhout, The Netherlands in 2007. The first act of asexual production of 'Zanmukatyl' was accomplished when vegetative cuttings from the initial selection in 2007 were propagated further in a controlled environment in Rijsenhout, The Netherlands. In summer, about 6-8 days are needed to initiate roots in cuttings of the new cultivar, after another 5 days rooted plants are formed. The new cultivar has been found to retain its distinctive characteristics through successive propagations.

2

BRIEF DESCRIPTION OF THE DRAWINGS

The present invention of a new and distinct variety of *Chrysanthemum* (of about 16 weeks) is shown in the accompanying drawings, the color being as nearly true as possible with color photographs of this type.

FIG. 1 shows a plant of the cultivar in full bloom.

FIG. 2 shows the various stages of bloom of the new cultivar.

FIG. 3 shows the various stages of foliage of the new cultivar.

DESCRIPTION OF THE INVENTION

15 The observations and measurements were gathered from plants, in the period of 15 to 20 weeks of age, grown outdoor in Rijsenhout, The Netherlands, under natural day length and temperature and planted in week 23 in 2013 (with a warm summer), receiving drip irrigation. The natural blooming date of this crop was September 9-14 (week 37). The average height of the plants was 55-60 cm. No growth retardants were used. No tests were done on disease or insect resistance or susceptibility. No tests were done on cold or drought tolerance. This new variety produces medium sized blooms with yellow inflorescences with a dark center blooming for a period of 5 weeks.

20 From the cultivars known to the inventor the most similar existing cultivar in comparison to 'Zanmukatyl' is its parent 'Katelli' (U.S. Plant Pat. No. 16,674.) When 'Zanmukatyl' and 'Katellil' are being compared the following differences are noticed. (1) Color center inflorescences. And (2). Ray-floret color. (1). Inflorescences of 'Zanmukatyl' have an orange center, while those of 'Katelli' have a dark red center. (2). Ray-florets of 'Zanmukatyl' are yellow, while those of 'Katelli' are orange.

The following is a description of the plant and characteristics that distinguish 'Zanmukatyl' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour Chart, edition 2001.

TABLE 1

Botanical Description of <i>Chrysanthemum × morifolium</i> Ramat. 'Zanmukatyl'		
Bud		
Size:	Small; cross-section 7-7.5 mm, height 4 mm	
Shape:	Round	
Texture:	Pubescent	
Outside color:	Greyed-green 191A	
Phyllaries		
Number:	22-24, arranged in 3 rows	
Shape:	Elliptic	
Apex:	Acute	
Base:	Truncate	
Margin:	Entire	
Color:	Upper side: Green 139B Lower side: Green 143C	
Length and width:	5-6 mm; 2-3 mm	
Texture:	Pubescent	
Inflorescences		
Type:	Double	
Height:	2 cm	
Diameter:	5.8-6 cm	
Peduncle length:	13-15 cm	
Peduncle color:	Green 138B	
Peduncle diameter:	1.8 mm	
Peduncle texture:	Pubescent	
Peduncle strength:	Weak	
Number per branch:	About 5-6 inflorescences	
Duration of flowering:	5 weeks	
Seeds:	Produced in small quantities, ovate, Greyed-brown 199A, length 1.5 mm, diameter 0.5 mm; texture: rough with ribs	
Fragrance:	Faint <i>chrysanthemum</i> odor	
Color inflorescences		
Center of inflorescence:	Immature stage: Yellow-orange 14A; Mature stage: Yellow-orange 14A	
Color of upper side of ray florets:	Yellow 7A	
Color of lower side of ray florets:	Yellow 7C	
Tonality from distance:	A garden mum with decorative yellow blooms and an orange hue in the center	
Color of ray florets after aging of the plant:	Greyed-yellow 162B	
Ray florets		
Type:	Ligulate	
Texture:	Upper and lower side smooth	
Number:	260-280	
Shape:	elliptic to narrowly elliptic	
Apex:	dentate	
Base:	attenuate	
Cross-section:	flat	
Longitudinal axis:	straight	
Length of corolla tube:	1-2 mm	
Diameter corolla tube:	0.9-1 mm	
Ray floret margin:	Entire	
Ray floret length:	1.2-2.5 cm	
Ray floret width:	1.5-6 mm	
Ratio length/width:	Medium	
Disc florets	absent	

TABLE 1-continued

Botanical Description of <i>Chrysanthemum × morifolium</i> Ramat. 'Zanmukatyl'		
Receptacle		
Color:	Yellow-green 145D	
Shape:	Conical raised	
Height:	4 mm	
Diameter:	2.5 mm	
Reproductive Organs		
Androecium:	absent	
Pollen color:	absent	
Gynoecium:	Present on ray florets	
Style color:	Yellow-green 154C	
Style length:	4 mm	
Stigma color:	Yellow 7A	
Stigma width:	1 mm	
Ovary:	Enclosed in calyx; color: Yellow-green 149D	
Plant		
Type:	Bushy	
Growth habit:	Spherical shape	
Growth rate:	Vigorous	
Height:	55-60 cm	
Width:	35 cm	
Stem color:	Greyed-brown 199A	
Stem strength:	weak	
Stem brittleness:	brittle	
Stem anthocyanin coloration:	absent	
Internode length:	1.5-3 cm	
Length of lateral branch:	From top to bottom 25 cm	
Lateral branch color:	Green 137C	
Lateral branch, attachment:	Weak	
Lateral branch diameter:	2 mm	
Lateral branch texture:	Pubescent with ribs	
Branching (average number of lateral branches):	Dense, with 9 breaks after pinching	
Natural season blooming date:	September 9-14 (week 37) in Rijsenhout, The Netherlands	
Roots - habits:	Freely branching, fine	
Roots - colour:	White 155D	
Foliage		
Glossiness:	Leaf upper side: weak Leaf lower side: absent	
Leaf color:	Upper side: Green 138A Lower side: Green 139C	
Color midvein:	Upper side: Yellow-green 147D Lower side: Yellow-green 148D	
Size:	Small; length 3-4.5 cm, width 1.5-2.5 cm	
Quantity (number per lateral branches):	22-26	
Shape:	Elliptic	
Texture upper side:	Sparsely pubescent	
Texture under side:	Pubescent	
Venation arrangement:	Palmate	
Shape of margin:	Serrated	
Shape of base of sinus between lateral lobes:	Rounded	
Margin of sinus between lateral lobes:	Diverging	
Shape of base:	Acute	
Apex:	Mucronulate	
Petiole attitude:	Moderately upwards	
Petiole length:	0.5-0.8 cm	
Petiole diameter:	2-3 mm	
Petiole color:	Yellow-green 147D	
Stipule:	Small, about 1 mm

TABLE 2

Differences with the comparison variety, when grown under identical conditions		
	'Katelli'	'Zanmukatyel'
Color center inflorescence	Greyed-red 178A	Yellow-orange 14A
Color ray-florets	Greyed-orange 163A	Yellow 7A

5

I claim:

1. A new and distinct *Chrysanthemum* plant named 'Zanmukatyel' as described and illustrated.
